Primary Examiner—Joel Sincavage

Attorney, Agent, or Firm—Burns, Doane, Swecker & Mathis[57] **CLAIM**

The ornamental design for a parallel mounting hybrid modular electrical signal connector, as shown and described.

DESCRIPTION

FIG. 1 is a perspective view as seen from the front and upper right of a parallel mounting hybrid modular electrical signal connector showing my new design;

FIG. 2 is a front elevational view thereof;

FIG. 3 is a left side elevational view thereof;

FIG. 4 is a back elevational view thereof;

FIG. 5 is a right side elevational view thereof;

FIG. 6 is a top plan view thereof;

FIG. 7 is a bottom plan view thereof;

FIG. 8 is a perspective view as seen from the rear and lower left thereof; and,

FIG. 9 is a sectional view thereof taken along line 9—9 of FIG. 2.

The cross-sectional view is included for the purpose of showing surface contours which may not be clear from the remaining illustrations. Any features of internal construction shown are incidental and form no part of the claimed design.
